CONNECTOR

John D. Benfield, Grosse Pointe Woods, Mich.

Application February 25, 1941, Serial No. 380,503

2 Claims. (Cl. 174—87)

This invention relates to connectors and more particularly to connectors formed from plastic, wood or any other suitable non-metallic material, and is adapted particularly for securing together the ends of a plurality of wires, metal tubing, metallic ribbons, or the like, and especially electric conductors of various sorts which are adapted to be grouped or bound together to provide joints, splices, taps or terminals. While the present invention is intended to be used in connection with the securing together of a plurality of electric conductors, it will be understood that it may be used for various other purposes. If desired, therefore, and in accordance with the present invention, the connector proper may be formed of metal by casting, forging or in any other suitable manner for binding together members other than electric conductors.

One of the objects of the present invention is to provide a connector of the foregoing character which is capable of making a positive joint or connection between two or more electric conductors without any danger of the accidental loosening or separation of said conductors, and one in which there is little chance of the electrician or other workman on the job to make any mistake in the completion of the joint or connection between the conductors so as to permit the joint or connection to come loose and ineffective during use.

Another object of the present invention is to provide a connector of the foregoing character which is "fool-proof" in use since it is impossible to tighten the parts of the present improved connector until and unless the conductors, which are to be spliced or secured together by means thereof, are in their proper positions with relation to the parts of the connector.

A further object of the present invention is to provide a connector of the foregoing character which has a universal range, that is to say one which is capable of receiving and connecting together a plurality of conductors, such as wires, wherein the conductors or wires themselves vary over a very wide range of sizes and combinations of wire groupings. In other words the improved connector is not limited to the binding together of any given size or grouping of conductors but will operate successfully on any size grouping from a size approximating the maximum of the loop opening down to zero.

A further object of the invention is to provide an improved connector of the foregoing character in which, by virtue of its novel construction, can be used to bind or secure together a plural-

ity of conductors or wires without any danger of damaging said wires, regardless of carelessness or abuse on the part of the workman, while at the same time maintaining them bound together in a group under pressure to prevent loosening of the wires and because of the pressure contact, the possibility of the corrosion of the wires or other conductors is greatly reduced.

A further object of the present invention is to provide an improved connector having means which, when applied to the ends of the conductors to be secured together, serves to force the several conductors or wires into one compact group, thus making the joint or connection electrically efficient and because of the pressure set up by the binding together of these wires, the possibility of corrosion which would destroy the contact through disintegration and loosening is substantially overcome.

Another object of the present invention is to provide an improved connector of the foregoing character having adjustable means for securing or binding the conductors or other members together in a compact mass and one in which, by virtue of its particular construction and arrangement of parts, the conductors are bound together more firmly due to the angularity of the gripping means of the connector or joint, in direct proportion to the amount of pulling force exerted directly upon the conductors themselves in a direction which would tend to separate or disassemble the conductors from the connector itself.

A further object of the present invention is to provide an improved connector of the foregoing character in which a wall of the connector is provided with knockout means which may be removed if desired, thus permitting the insertion of additional conductors or wires to be coupled together, spliced or connected with the previously inserted wires, or used as a two way connector for only two wires.

Another object of the present invention is to provide an improved connector of the foregoing character in which the tightening together of the parts of the connector causes a binding action on the conductors or wires passing thereto and in which accidental loosening of the conductor parts is prevented, thus eliminating any possibility of loosening and slippage of the conductors or wires.

A further object of the present invention is to provide an improved connector having positive locking means in which the several parts of the connector are automatically bound and locked

together as the connector is installed upon the conductors by the workman.

A further object of the present invention is to provide an improved connector which may be easily applied to a plurality of wires or other conductors to connect them together without requiring the use of any special tools.

A further object of the present invention is to provide an improved connector of the foregoing character which is of relatively simple construction, having a minimum of parts, and one which can be produced at low cost and at high production rates.

The foregoing and other objects and advantages of the present invention will appear from the following description and appended claims when considered in connection with the accompanying drawing wherein like reference characters designate corresponding parts in the several views.

In said drawing:

Fig. 1 is an elevational view of a connector embodying the present invention showing one of its applications of use.

Fig. 2 is an enlarged vertical sectional view, partly in elevation, of an improved connector embodying the present invention.

Fig. 3 is a longitudinal sectional view taken substantially along the line 3—3 of Fig. 2, looking in the direction of the arrows.

Fig. 4 is a sectional view taken substantially along the line 4—4 of Fig. 2, looking in the direction of the arrows.

Fig. 5 is an exploded view of the connector of Figs. 2 to 4 inclusive.

Fig. 6 is an elevational view of one end or wall of the body portion of the connector of the preceding views; and

Fig. 7 is a perspective view of a somewhat modified form of connector embodying the present invention.

Before explaining in detail the present invention it is to be understood that the invention is not limited in its application to the details of construction and arrangement of parts illustrated in the accompanying drawing, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

Referring now particularly to Figs. 1 to 6 inclusive of the drawing, A represents as a whole an improved connector embodying the present invention. As shown, this connector comprises a body portion B, a removable or detachable cap member C, and an adjustable gripping or clamping member D.

The body portion, as shown, is preferably formed from some non-metallic material such as plastic, wood, hard rubber, or the like, and is provided at its upper or top end with a preferably cylindrical pocket or cup 10. The body portion B is provided with a bore or socket portion 11 which extends from the bottom of the cup portion 10 to the lower or bottom wall 12 of the body portion. The bottom wall or portion 12, is, as shown, provided with a recessed cap or disk-like portion 13 which is formed integrally with the remainder of the body portion and which serves as a bottom or end wall for the socket 11. The disk-like portion 13 is, as shown, set

in, or countersunk for a purpose to be described hereinafter.

The diameter of the cup portion 10 is considerably larger than that of the bore or socket 11, this for the purpose of permitting the reception of the insulated ends of a number of electric conductors such as the wires W shown in Figs. 1 and 2. It will be understood that before the ends of the wires W are inserted in the socket or bore 11, the insulation adjacent the ends thereof is cut and skinned so that the bare ends of the wires 11 are exposed. These exposed bare ends of the wires 11 are either twisted together or grouped together straight before they are inserted as a group into the socket or bore 11.

The body member B is preferably provided with an offset portion of generally round or cylindrical form which extends beyond the main body portion at an acute angle thereto. This offset portion of the body is indicated generally at 14 and, as shown, is provided with a cylindrical bore or recess 15 which extends from the outer face of the portion inwardly to a point adjacent the socket or bore 11 in the main body.

As best seen in Figs. 2 and 5, the offset portion 14 at diametrically opposite points defining the cylindrical bore 15, is provided with a keyway or slideway 16. It will be seen, by particular reference to Figs. 2 and 5, that this keyway or slideway 16 extends through the offset portion of the body and through the main portion of the body B and defines the opposite upright walls of the socket or bore 11. This keyway or slideway 16 terminates in an arcuate extension 16a formed in an upright wall of the main body portion. The cylindrical bore in the offset body portion 14 terminates in a frusto-conical seat or inner end portion 17.

The offset portion 14 is provided with a flat outer face 18 and with tapered surfaces 19. These tapered surfaces, see particularly Fig. 6, provide a plurality of cam faces or portions 20. As shown, four such cam faces 20, although more such faces could be employed are provided and it will be understood that each cam face is worked from zero up to an elevation of approximately $\frac{1}{64}$ of an inch in a gradual taper. The high point of each of the cam faces then tapers off abruptly at approximately a 45° angle, as shown at 21, to zero at the juncture of the next adjacent cam face 20.

The cam faces 20 and 21 are alternated throughout the circumference of the tapered surface 19 of the projecting or offset portion 14 of the body. The arrangement of cam faces, as described, is worked out on the basis of a right hand thread.

The keyway or slideway 16, 16a together with the centrally disposed cylindrical bore or socket portion 15, provide means for receiving and slidably supporting the clamping or gripping member D previously referred to. This member D, as shown, is of generally elliptical form having its inner end generally triangular in shape, said member being preferably in the form of a loop 25 having an opening 26 therein and being provided with an outwardly extending externally threaded shank or portion 27. The inner edge of the substantially triangular portion 25a of the loop is provided with a plurality of teeth or serrations 28. The teeth or serrations 28 are adapted to grip the exposed ends of the wires W when the clamping or gripping member D is moved outwardly toward the body offset or extension 14. It is to be understood that the cross section

of the keyways or slideways 16 is substantially rectangular and that the thickness and size of the loop portion 25 of the gripping device is such as to have a relatively snug fit in the guideway, there being only sufficient tolerance or clearance between the parts to permit of the sliding movement of the gripping device D longitudinally of the guideway 16, 16a. Moreover, it is to be understood that the portion of the member D which extends between the inner end of the threaded shank 27 and the adjacent side of the opening 26 in the loop, is of sufficient thickness to substantially fill the space 16b (see particularly Fig. 5) between the socket 11 and the bore 15.

The connector of the present invention is provided with an adjustable knob or cap member referred to above and designated as a whole by the reference letter C. This member C, as shown, is preferably formed of the same material or at least material generally similar to that from which the body B of the connector is formed and, as shown, is provided with a threaded insert or bushing member 30. This member, as shown, is externally serrated to anchor it into the composition or plastic and also provided with internal threads 31 which are adapted to cooperate with the threaded portion of the shank 27 of the gripping or clamping device D.

By particular reference to Figs. 2 and 5, it will be seen that the cap C is provided with a closed end 32 and with an inwardly tapered socket or cup-like forward portion 33. This portion 33 is shaped and designed to correspond to and cooperate with the tapered portion 19 of the body B. In other words, the internal taper 33 of the cap coincides or corresponds to the external taper 19 of the body B. The tapered inner face 33 of the cap member C is provided with a series of cam faces having portions 34 and 35 which correspond to and cooperate with the cam portions or faces 20 and 21, respectively, of the body B. Therefore, upon applying the cap C to the tapered surface of body B, the parts 33 and 19 will have cooperating cam surfaces so that upon rotation of the cap in a clock-wise direction relative to the body the cam surfaces will ride over the cam surfaces of the body member B until the loop or gripping member D binds upon the conductors W whereupon the cap C is drawn toward the body B to cause the cam faces 20, 21 and 34, 35 to automatically lock the cap C and the entire assembly together as a unit.

By virtue of the fact that the cam faces above referred to have a gradual taper in a clockwise direction and an abrupt taper in a counter-clockwise direction, it is relatively easy to turn the cap C into locked position thereby holding the parts firmly together, but once the parts are locked together, it is difficult to release the cap from its locked position. But, because of the approximately 45° taper of the cam faces 21 and 35, it is possible to manually unlock or release the parts for inspection or changes.

It will be understood that the three parts of the connector heretofore described, namely the body portion B, the gripping member D and the cap C are separate parts which are adapted to be easily assembled as a unit. It will also be understood that it is impossible to maintain the cap C in place upon the body B and the clamping or gripping member D within the guideway B unless some member or members, such as the group of electric conductors or wires W projects into the socket portion 11 and through the opening 26 formed in the loop of the clamping member D,

in which case the conductors or wires become the means to hold the parts of the connector assembled together.

One application or manner of installation of the improved connector of the present invention may be substantially as follows:

Assuming that the three wires W are to be electrically connected, the insulation from these wires adjacent their free ends is first cut and then skinned off so as to expose the actual metal wires at and adjacent their ends. These exposed portions of the wires are then twisted together or grouped together without twisting and the whole inserted into the body portion B of the connector, with the insulated portions of the wires adjacent their stripped ends fitting within and being seated in the cup portion 10 of the connector. With the wires in this position, and the adjustable clamping or gripping member D in place in the guideway 16, 16a, the bore or raw end portions of the wires W extend through the hole or opening 26 in the loop of said gripping member and inwardly or downwardly, as shown, toward the wall portion 13 of the connector body. With the parts in this position, the cap member C is applied to the threaded shank 27 of the gripping member D and rotated in a clockwise direction. The cooperation of the threads on the metal insert 30 of the cap with the threads on the shank 27 serves, upon rotation of the cap in a clockwise direction, to draw the threaded shank outwardly or toward the closed end wall 32 of the cap. Such action moves or shifts the clamping member D toward the cap C and the loop of said member D will bind the end portions of the wires W against the adjacent wall of the socket portion 11 of the connector body. It is to be noted that the slots 16 and the slideable gripping member D, as shown, extend at an acute angle to the socket member or portion 11. This angle may vary but as shown is approximately 23 degrees with relation to the socket 11. Thus, as the looped portion 25 of the member D is drawn inwardly toward the offset portion 14 of the body, the serrations or teeth 28 of the loop will grip the wires W and further inward movement by virtue of tightening the cap C will cause these several wires W to be firmly gripped and compressed by the loop and also locked or bound under pressure. Such binding together of the wires and maintaining them under pressure at all times prevents any possibility of the individual wires becoming loose and slipping out of the connector. The pressure connection likewise reduces the possibility of an accumulation of corrosion on the exposed ends of the wires.

Referring now particularly to the disk-like portion or knock-out plug 13, it will be understood that by virtue of the fact that this plug or disk is set in from the outer face of the bottom or base wall 12 of the body portion B the mechanic on the job will immediately recognize the fact that this is the thin walled portion of said body which can be removed if desired and will break it or punch it out. Such removal will permit the insertion into the bore or socket portion 11 of an additional electric conductor or a plurality of such conductors, such, for example, as the conductor or wire shown at E in Fig. 1 of the drawing. After the knock-out plug or disk 13 has been removed, the cap C may be turned in a counter-clockwise direction to loosen the pressure upon the ends of the wires or conductors W, whereupon the additional conductor or wire E, or plurality of such, may be inserted through the

opening or loop 26 of the clamping member D and the cap C rotated in the opposite or clockwise direction to again tighten the parts together to lock or bind the wires or conductors E and W together as a unit and hold them so bound under pressure. While the wall portion or plug 13 is, as shown, thinner than the adjacent walls of the connector, it will be understood that this portion is of sufficient strength and thickness so as to withstand wear and usage along with the remaining parts of the connector. Because of the fact that the connector has been provided with the disk-like portion or knock-out plug 13, it may be adapted for additional uses without in anywise affecting the utility, strength and durability of the connector.

In Fig. 7 of the drawing, there is shown a somewhat modified form of connector embodying the present invention. In this form of the invention, the connector body portion or member is shown as a whole at B' and the removable cap member at C'. It will be seen that the body portion is provided with a slot or keyway 16 which corresponds to the slot or keyway of the preceding form of the invention and that, as shown, the removable cap C' is also provided with a threaded insert or bushing 30 corresponding to the bushing of the preceding form.

Instead of providing tapered cam faces for the cooperating portions of the body member B' and the cap C' as in the preceding form, the adjacent ends of these members of the present connector are provided with ratchet-like teeth or serrations. The body member B' has a plurality of teeth or serrations 40 and the cap member or portion C' is provided on its inner face or surface with a series or plurality of similar teeth or serrations 41. These teeth or serrations on the coacting or cooperating members are adapted to permit the cap member C' to be rotated in a clockwise direction to secure or lock the parts together and to hold said cap in such locked condition against accidental loosening or displacement relative to the member B'. By turning the cap C' in a clockwise direction, it will be understood that the clamping device D (not shown in connection with Fig. 7) will be drawn outwardly or downwardly toward the cap so as to bind the exposed ends of any electrical conductors or wires or other flexible members positioned within the body portion or member toward the wall of the bore or socket 11 which is nearest to the cap and thus lock or bind said wires together in position under pressure within the connector. In other words, the wires are bound or locked in place within the connector of Fig. 7 in precisely the same manner as in the connector of the preceding views. It will be understood that the teeth or serrations 40 and 41 are so shaped and proportioned as to permit of the cooperation and interlocking of parts to maintain the cap C' in locked position upon the body B'. Thus, it will be seen, that the parts of the connector shown in Fig. 7 of the drawing will be held together in similar manner to the parts B and C of the preceding form. While the ratchet-like teeth or serrations 40 and 41 coact to maintain the parts in locked condition when the cap is turned in a clockwise direction, it is possible by virtue of the shape and formation of said teeth, to turn the cap member C' in a counterclockwise direction so as to remove the binding action or pressure on the flexible members or electric conductors to release them when and if desirable.

While the cap member C is shown as being

provided with a metal insert or sleeve member 30, it will be understood that the cap member itself may be internally threaded with the threads formed from the material of the cap so as to cooperate with the threaded end portion 27 of the slideable clamping member D.

From the foregoing it will be seen that I have provided improved connectors for use in securing together, under pressure, a plurality of flexible members, such for example, as electric conductors, wires, or the like, which have universal use in that a connector of a given size is adapted to accommodate a wide range of flexible members or wires of different sizes and grouping.

Moreover, it will be seen that I have provided improved connectors which are of relatively simple construction, durable in use, and which may be cast, molded or otherwise produced from materials of various kinds at relatively low cost.

I claim:

1. In a connector for binding together a plurality of flexible members under pressure, a body member having a cup-like socket formed therein and a substantially cylindrical bore forming a continuation of said socket for receiving the end portions of the flexible members, said body member having a keyway extending therein at an acute angle to said bore, said body member also having an offset portion provided with a substantially cylindrical bore extending at substantially the angle of said keyway, a clamping member having a relatively snug fit in said keyway and slideable longitudinally therein, said clamping member having a loop portion cooperable with said first named bore and a threaded shank portion normally fitting within said second bore, and a removable and rotatable cap member threadedly engaging said shank for moving said clamping member in a longitudinal direction in the keyway to draw the clamping member toward said cap member and clamp or bind the flexible members under pressure between the loop portion of said clamping member and the adjacent wall of the first named bore, said offset portion and said cap member having releasable cooperating locking means formed on their adjacent faces, the cooperating faces of said offset portion and said cap member extending at angles of approximately 45° whereby to hold the parts in alignment and thus reduce the possibility of breakage or splitting of the body in the location of said keyway upon rotation of the cap member into locked condition.

2. In a connector for binding together a plurality of flexible members under pressure, a body member formed from plastic material having a cup-like socket formed therein and a substantially cylindrical bore forming a continuation of said socket for receiving the end portions of the flexible members, said body member having a keyway extending therein at an acute angle to said bore, said body member also having an offset portion provided with a substantially cylindrical bore extending at substantially the angle of said keyway, a clamping member having a relatively snug fit in said keyway and slideable longitudinally therein, said clamping member having a loop portion provided with teeth cooperable with said first named bore and a threaded shank portion normally fitting within said second bore, and a removable and rotatable cap member formed from plastic material and having a threaded metallic insert engaging said shank for moving said clamping member in a longitudinal direction in the keyway to clamp

or bind the flexible members under pressure between the loop portion of said clamping member and the adjacent wall of the first named bore, said offset portion and said cap member having releasable cooperating locking means formed on their adjacent faces, the cooperating faces of said offset portion and said cap mem-

ber extending at angles of approximately 45° whereby to hold the parts in alignment and thus reduce the possibility of breakage or splitting of the body in the location of said keyway upon rotation of the cap member into locked condition.

JOHN D. BENFIELD.
